UNITED STATES PATENT OFFICE.

FRANK J. HERRICK, OF NEW BRITAIN, CONNECTICUT, ASSIGNOR TO THE NORTH & JUDD MANUFACTURING COMPANY, OF SAME PLACE.

DESIGN FOR A RAZOR-STROP.

SPECIFICATION forming part of Design No. 22,871, dated November 7, 1893.

Application filed May 4, 1893. Serial No. 473,023. Term of patent 7 years.

To all whom it may concern:

Be it known that I, FRANK J. HERRICK, a citizen of the United States, residing at New Britain, in the county of Hartford and State of Connecticut, have invented and produced a new and original Design for a Razor-Strop, of which the following is a specification, reference being had to the accompanying drawings, forming part thereof, in which—

10 Figure 1 is a plan view of a razor strop showing my design. Fig. 2 is an edge view of the same, and Fig. 3 is a reverse plan view of the same.

15 A designates the body of the strop at one end of which is a rectangular frame B the longer sides of which frame are formed by the rounded bars 5 and 6. Between these bars and parallel to the bar 5, the bars 4 and

7 are formed on said frame as shown. A ring shaped eye 8 projects from the middle portion of the bar 6 of the frame B, as shown. At the opposite end of the body of the strop is a similar rectangular frame, formed of like bars arranged in the same order and having the T shaped handle D extending from the middle portion of its bar 6, the cross arm of the T being in the same general plan as the frame C.

20 What I claim is—

25 The design for the shape of the article of manufacture the razor strop herein shown and described.

FRANK J. HERRICK.
